UNITED STATES PATENT OFFICE.

EDWARD S. CHAPIN, OF NEW YORK, N. Y.

SULFUR DYE AND PROCESS OF MAKING SAME.

No. 903,151.

Specification of Letters Patent.

Patented Jan. 12, 1908.

Application filed February 19, 1898, Serial No. 801,902. Renewed September 24, 1903. Serial No. 454,529.

To all whom it may concern:

Be it known that I, EDWARD S. CHAPIN, a citizen of the United States, and a resident of the borough of Brooklyn, city and State of New York, have invented certain new and useful Improvements in Sulfur Colors and Processes for Making the Same, of which the following is a specification.

My invention consists in heating a non-crystallizable polysaccharid (Tollens "Kohlenhydrate" Breslau 1895, Vol. II, pp. 197-276) with the usual sulfurizing substances until a stable non-hygroscopic, easily pulverizable or pulverulent substance is formed.

15 Bretonnière, in 1873 (U. S. Patent No. 142,892, September 18, 1873; French Patent No. 90,915, July 29, 1873; British Patent No. 1,480, April 24, 1873) discovered a

20 method of sulfurizing various organic bodies, including members of the group of non-crystallizable polysaccharids, to produce coloring matters. Coloring matters manufactured in accordance with his invention were placed upon the market by Société Anonyme des Matières Colorantes et Produits Chimiques de St. Denis (Poirrier) at St. Denis, Paris, France, under the name of "Cachou de Laval", and sold for a number of years until they were displaced by the sulfur col-

30 ors made from aromatic chemicals. See "The Journal of the Society of Chemical Industry," 1893, page 328, "Cachou de Laval" by F. W. Richardson and H. E. Aykroyd; also "Chemie des Stärkelehrers"

35 S. Altz, Vol. II, p. 405. This "Cachou de Laval" was a highly hygroscopic material.

In his American patent, page 2, column 2, Bretonnière says: "The products should be preserved in air and water tight cases." This

40 characteristic is noted in Dingler, No. 911, 1874, p. 404 "Über Neue Färbende Mat-

terien, von C. Croissant & L. Bretonnière"; also in Dingler, No. 215, 1875, p. 363 "Die

45 Schwefelhaltigen Organischen Farbstoffe von Croissant & Bretonnière": "They (the

products) are all very hygroscopic and must therefore be kept in well closed tin boxes to

protect them from the influence of moisture and the consequent absorption of oxygen

50 from the air. The latter oxidizes the colors and converts them into an insoluble sub-

stance and thus decreases their dyeing effi-

ciency; without this precaution they be-

come, in four or five months, entirely in-

55 soluble and useless." See also *Journal of the*

Society of Chemical Industry 1896, p. 328, paper on "Cachou de Laval" by Richardson & Aykroyd, particularly the "Discussion" in which Mr. C. Rawson pointed out that "Cachou de Laval" deteriorated somewhat rapidly if not preserved in well-closed vessels", and in which Mr. Richardson stated that "they had found that the deliquescent substances contained in 'Cachou de Laval' caused it to absorb moisture from the air rapidly (as much as 18 per cent. in a night), and that accompanying this an oxidation took place which first caused the coloring matter to dye browner shades and which diminished its coloring power very considerably". See also "A Manual of Dyeing", Knecht, Rawson & Loewenthal, Vol. II, p. 635: "It greedily absorbs moisture and air, thus becoming insoluble by oxidation".

75 While "Cachou de Laval" was a substantive color, it was necessary to fix it by means of a metal or acid bath. Bretonnière, in his American patent, page 2, column 1, speaks of fixing the colors by means of bichromate of potash. See also the articles in Dingler No. 211, 1874, p. 404; No. 215, 1875, p. 363; same, p. 561. Rawson, Gardner & Laycock in their "Dictionary of Dyes" p. 70, Art. "Cachou de Laval" mention sulfuric and hydrochloric acid, bichromate of potash, copper sulfate and ferric sulfate as fixing substances. Knecht, Rawson & Loewenthal, in their "Manual of Dyeing" Vol. II, p. 635, Art. "Cachou de Laval" speak of fixing the colors after dyeing "especially by means of certain acids or metallic salts, such as nitric acid, bichromate or permanganate of potash, nitrate of iron, etc."

95 I have discovered that by using the same non-crystallizable polysaccharids as those used by Bretonnière, Croissant, and Poirier in the manufacture of "Cachou de Laval", but by subjecting these substances to a certain degree of heat until a non-hygroscopic, easily pulverized substance is formed, I obtain coloring matters different from "Cachou de Laval". The coloring matters thus obtained need not be kept in air and water tight receptacles, as they are non-hygroscopic and lose little of their dyeing powers by ordinary exposure to air; and need not be fixed by metals, acids or other means, although they may be aftertreated with

100

105

110

copper sulfate to increase their fastness to light. They dye cotton directly in a salt bath with the addition of sodium sulfid or salsoda—and are of a strength incomparably greater than that of Cachou de Laval.

While it is probable that at a certain stage of my process Cachou de Laval is formed, my process does not stop at that stage but 10 continues by the further application of heat until a different substance is formed.

I have sulfured a great variety of non-crystallizable polysaccharids by my process, and have uniformly obtained satisfactory 15 results. I have used for instance: corn-starch, potato starch, wheat starch, wheat flour, rice starch, tapioca, sago, arrowroot, soluble starch, iodized starch, corn dextrin, potato and various commercial brands of 20 dextrin, gum arabic, gum tragacanth, flax seed, aloes, turmeric and wood sawdust. The sulfuring agents which I prefer to use are sodium sulfid crystals, $\text{Na}_2\text{S}+9\text{Aq}$, and 25 sulfur. I may secure similar results by using caustic soda and sulfur, or carbonate of soda and sulfur.

I have found that certain differences exist among the polysaccharids as regards their reactivity with the sulfuring agents. 30 Thus the starches and gum arabic even at a boiling temperature begin to react with the sulfuring agents. At 140° C . the reaction goes forward well. With increase of temperature this continues, and the product 35 is finished at $200\text{--}230^\circ\text{ C}$. On the other hand with wood-sawdust no reaction occurs at all until the temperature is over 200° C . and the finished results are secured at about 250° C.

40 The differences in reactivity noted correspond in a small way to differences in the resultant coloring matters. The coloring matters from the starches and gum arabic are somewhat blacker and redder than that obtained from wood sawdust. This latter is distinguished by a yellowish tone. The shades of the resultant coloring matters, however, are all dark to black browns. The products from the starches and gum arabic 45 are practically identical in shade. While it is possible to obtain wider variations in shade by stopping the process before the greatest concentration of color is developed, this is undesirable, and it may be said that 50 doubtless all the resulting products are individuals of a family of coloring matters closely allied to each other if not perhaps practically identical in chemical composition. These products are all distinguished 55 by their excellent fastness to alkalies, acids and fulling. This fastness is increased by aftertreatment with bichromate of potash, chromium fluorid, or bluestone. They are somewhat relatively inferior as regards 60 their fastness to light, but this latter can

be improved greatly by aftertreating the products with bluestone.

The following examples will serve to illustrate the manner in which coloring matters may be produced from the non-crystallizable polysaccharids by my process.

Example I. Corn, wheat or potato starch used as a basis.—Into a suitable crucible weigh out 60 grams of sodium sulfid crystals, 15 grams of sulfur and add 200 c. c. 70 of water. Bring to a boil. Then add 15 grams of wheat, corn or potato starch worked up into a thin paste with 50 c. c. of cold water. Bring to a boil, and evaporate the water. Raise the temperature slowly to 80 140° C . and heat at that temperature for about 1 hour; then raise to 200° to 220° C . and heat another hour. The contents of the crucible should be stirred well throughout the operation: though the cover should be 85 in place as much as possible to prevent burning and insure uniform heating. The mass should be dry, partially pulverized and readily pulverizable. If on dyeing the color is not up to standard strength, its maximum, 90 the heating should be continued for another half hour at $200\text{--}220^\circ\text{ C}$. The substance obtained by this process is readily soluble in cold water to a greenish black solution; readily soluble in cold alcohol, cold caustic 95 carbonate of soda solutions; and dyes cotton in the regular salt bath fast dark brown shades inclined to a reddish tone with the assistance of sodium sulfid or sal soda. The coloring matter is a dry, pulverizable substance, which does not attract moisture on standing, and loses practically none of its tintorial power on ordinary exposure to air.

Example II. Sawdust used as a basis.—105 Into a suitable crucible weigh out 60 grams of sodium sulfid crystals, 15 grams of sulfur and 200 c. c. of water. Bring to a boil at once, and add 15 grams of wood sawdust. Boil one hour. No reaction takes place, but 110 experiments have shown that better results are obtained with this preliminary boil probably because the sawdust thereby becomes well impregnated with the sulfuring agent. Evaporate the water and raise the 115 temperature slowly to 250° C . and heat at that temperature for forty to sixty minutes in a closed vessel. Burning takes place if the crucible is open and exposed to the air. The mass must be well stirred occasionally 120 to insure a uniform reaction. The resulting substance has the same general chemical properties as the substance produced by the process cited in Example I., and dyes cotton a somewhat less dark and yellower shade. 125

Example III. Gum arabic used as a basis.—Substitute in Example I gum arabic for the starch and add slightly more water during the preliminary boil. The resulting substance has the same general chemical 130

properties and dyes cotton the same shade as the substances made in accordance with Examples I and II. The substances should not be heated beyond the degree at which the blackest and heaviest results are obtained, as after that time, upon continued heating, they change their character and gradually lose their ability to dye cotton, turning into wool colors. The process of 10 making these wool colors may form the subject matter of later applications.

From all these original melts the coloring principle can be precipitated by an acid, for example hydrochloric acid, and obtained 15 in a purer form. The coloring matters thereby obtained are insoluble in water, or alcohol, but readily soluble in sodium sulfid solution to a greenish black solution, and dye cotton directly in a salt bath with the 20 assistance of salsoda and sodium sulfid fast dark brown shades, inclined to the red in the case of the starches and gum arabic, and yellow in the case of wood sawdust.

I claim:

- 25 1. The process of making coloring matters consisting in heating a non-crystallizable polysaccharid with sulfuring agents at a hereinbefore specified temperature, until a non-hygroscopic, readily pulverizable 30 dyestuff is formed.
2. The process of making coloring matters consisting in heating a non-crystallizable polysaccharid with sodium sulfid and sulfur at a hereinbefore specified temperature, until a non-hygroscopic readily pulverizable dyestuff is formed.
- 35 3. The process of making coloring matter

ters consisting in heating wood sawdust, with sulfuring agents at a hereinbefore specified temperature until a non-hygroscopic 40 readily pulverized dyestuff is obtained.

4. The process of making coloring matters consisting in heating wood sawdust with sodium sulfid and sulfur at a hereinbefore 45 specified temperature until a non-hygroscopic readily pulverizable dyestuff is obtained.

5. As a new article of manufacture the dark yellowish brown coloring matter which 50 can be made by heating wood sawdust, sodium sulfid and sulfur in the manner hereinbefore specified and which is non-hygroscopic, readily pulverized, readily soluble in cold water to a greenish solution, readily 55 soluble in cold alcohol, cold caustic and carbonate of soda solutions, and dyes cotton in the regular salt bath fast dark yellowish brown shades and which, when precipitated by an acid forms a dark yellowish brown 60 coloring matter which is insoluble in water or alcohol, but readily soluble in sodium sulfid to a greenish black solution, and dyes cotton directly in a salt bath with the assistance of sal soda and sodium sulfid fast dark 65 yellowish brown shades.

In testimony whereof, I have hereunto signed my name in the presence of two subscribing witnesses.

EDWARD S. CHAPIN.
